SEWING MACHINE

Phillip S. Morse, New York, N. Y.

Application May 25, 1953, Serial No. 25,180

Term of patent 14 years

(Cl. D70—1)

FIG.1

FIG.2

FIG. 3

FIG. 4

Figure 1 is a front perspective view of a sewing machine showing my new design;

Figure 2 is a rear perspective view thereof;

Figure 3 is a top view thereof;

Figure 4 is an end view taken from the left or head end; and

Figure 5 is an end view taken from the right end.

The dominant features of my design reside in those portions shown in full line.

I claim:

The ornamental design for a sewing machine, substantially as shown and described.
